APPARATUS FOR STABILIZING WELL DRILLS

Earl J. Robishaw, Houston, Tex., assignor to A-1 Bit & Tool Company, Houston, Tex., a corporation of Texas

Application May 13, 1949, Serial No. 92,998

4 Claims. (Cl. 255—28)

This invention relates to the art of drilling wells by the employment of a rotary stem provided with a bit and particularly an apparatus for stabilizing the drill.

In drilling wells or bore holes in the earth various types of formations are encountered and in drilling through them the drill does not necessarily rotate about the axis of the bore. This is particularly true as the drill stem becomes lengthened as the well is deepened since there is a certain amount of flexibility in the drill stem.

In other words the drill often wobbles and forms a bore hole of much greater transverse diameter than the transverse diameter of the drill. This delays the progress of the work, causes unnecessary removal of earth material from the bottom of the bore, and forms a bore hole of irregular transverse dimensions.

The drilling assembly used in drilling a well is made up of a drill bit which is connected to the lower end of the drill stem by means of a drill collar or collars. The overall transverse diameter of the drill is the same as the transverse diameter of the bore hole while the transverse diameter of the drill collar is somewhat less than said diameter of the drill and the transverse diameter of the drill stem is considerably less than the transverse diameter of the drill collar. So the only part of the assembly which is of the same transverse diameter as the bore hole is the drill itself. The drill is relatively short and is in contact with the walls of the bore hole for a relatively short distance, usually not more than twelve inches, and in most cases of less distance. It is, therefore, apparent that the drill collar can move from the axial center of the bore hole in all directions, and if the drill bit starts drifting it will drift progressively off-center without any hindrance except the tendency which might be described as a plumb bob effect produced by the heavy drill collar on the bottom of the relatively light drill pipe. It will further be seen that the greater the weight sustained by the drill the greater is the tendency for the bore hole to drift away from vertical.

In addition to the drifting effect, there are other conditions which prevail while drilling certain types of formation such, for example, as sandy shale. Under such conditions the drill bit may start oscillating and assume a regular oscillatory movement such that it will drill an out-of-round hole. If a fish tail bit is employed the hole will be substantially triangular in horizontal cross-section. If a three-way bit is employed the hole will be substantially square. In the case of a tricone rock drill the hole can be drilled substantially square in horizontal cross-section. Such holes while being drilled would not allow the passage of a round object of the same maximum transverse diameter of the drill being used because the minimum distance from one wall to the opposite one would be less than the maximum transverse diameter of the drill itself.

Another condition which often arises while drilling certain types of formation, such as shaly sand, where a fish tail bit is used, is that the drill bit ceases to operate about its central axis. In such case the drill pipe rotates normally but the drill bit revolves, or moves around, edgewise, thus forming a cone in the center of the hole. When this condition arises the drill bit is usually destroyed and in some cases the drill collar is also destroyed, because they are forced to slide around the bore of the hole and one side is continuously in contact

2

with the wall of the well bore. When this condition arises the rate of penetration of the drill bit drops to practically zero and the hole then drilled is oversized and extra formation is unnecessarily removed.

Because of the aforementioned conditions, where the hole drilled is larger than the drill itself and frequently many times as large, it follows that much more material will be drilled and to a greater volume than necessary to produce the desired bore hole. This not only decreases the efficiency of drilling many fold, but results in an undue enlargement of the hole, aggravating caving and requiring materially larger amounts of cement when a casing is cemented.

One of the objects of this invention, therefore, is to provide an apparatus whereby the above disadvantages may be overcome.

It is a further object of the invention to provide a stabilizer which will not drill but which merely floats on the drill stem, which will not resist in any manner upward or downward movement of the drilling tool, which will not retard circulation but will merely act as a stabilizer.

Under said conditions a single stabilizer may effectively maintain the drill bit centered with relation to the bore hole so as to drill a straight bore while under other conditions two, or more, of the stabilizers may be required as will be more specifically hereinafter set out.

It is still a further object of the present invention to provide stabilizing means which will be effective to drill away the sidewall formation of the well in case the equipment should become stuck in withdrawing the same from the well bore, or in lowering it into the bore.

Other objects and advantages will be apparent from the following specification which is illustrated by the accompanying drawings disclosing an illustrative embodiment of this invention; it is to be understood, however, that this invention is susceptible of various other embodiments within the scope of the appended claims without departing from the spirit of this invention. In the accompanying drawings:

Figure 1 is a vertical sectional view of the upper end of the stabilizer.

Figure 2 is a vertical sectional view of lower end thereof.

Figure 3 is a cross-sectional view taken on the line 3—3 of Figure 1.

Figure 4 is a cross-sectional view taken on the line 4—4 of Figure 2.

Figure 5 is an enlarged fragmentary side elevation of the stabilizer shown in a well bore.

Figure 6 is a side view of the complete assembly shown in the well bore.

Figure 7 is a side elevation of the upper end of the complete assembly in which a plurality of stabilizers are employed.

Figure 8 is an elevational view of an intermediate portion of said assembly.

Figure 9 is a side elevation of the lower end thereof; and

Figure 10 is a vertical sectional view of the upper end of another embodiment of the stabilizer, shown in Figure 1.

Generally stated and in accordance with illustrative embodiments of this invention, the drill stem is centered by a bearing in the bore hole above the bit and this bearing is released from the bore hole upon sticking thereof. This may be accomplished in various ways, such as by axial movement of the drill stem by jarring thereof by relative axial impact of the drill stem and the bearing and by clutching the bearing with the drill stem. The mechanism which may be employed for accomplishing the objects of this invention may embody generally a drill stem section arranged for coupling as a part of a drilling equipment, such as with the drill pipe above the section and with the bit below it. This drill stem section has a bearing in which the section is relatively rotatable, the bearing being dimensioned to center the stem section in the bore hole. Means is provided for releasing the bearing from the bore hole upon sticking thereof. This may be accomplished in various ways.

In an illustrative embodiment, the bearing is relatively slidable as well as relatively rotatable with respect to the stem section, and this provides for means operating upon axial movement of the section to release the bearing from the bore hole. Means may, however, be provided for clutching the bearing to the section either axially or rotatably, or both. Means is provided for jarring the section; thus, in an illustrative embodiment, this is accomplished by suddenly interrupting the relative sliding movement of the stem section and the bearing. The bearing may, however, have included in it a shear so that upon relative movement of the stem section and the bearing, the bearing will be released.

Referring now more particularly to Figures 1 to 6, inclusive, of the drawings, the numeral 1 designates a tubular drill stem which extends to the ground surface. Incorporated into this drill stem there is what is commonly known as a drill collar 1a.

In the present illustration there is the tubular stabilizer stem 2 screwed onto the lower end of the drill collar 1a, and attached to the lower end of the stabilizer stem there is a special coupling 3 to which any selected type of drill 4 may be connected.

It may be here stated that the drill collar 1a, the drill stem section or stabilizer stem 2, and the special coupling 3 all, in effect, are a part of the drill stem.

The upper end of stabilizer stem 2 is of approximately the same transverse diameter as that of the drill collar but it is reduced in transverse diameter forming the external, annular, downwardly facing shoulder 5 and on this shoulder there is an anti-friction thrust bearing 6.

Beneath this bearing assembly around the stabilizer stem 2 there is the bearing in the form of an elongated cylindrical stabilizer sleeve 7.

Between this sleeve and the stem 2 there are a plurality of series of anti-friction rollers 8 so that said stem will rotate freely independent of the rotation of said sleeve. Between the sleeve 7 and stem 2 above and beneath said anti-friction rollers there are the upper and lower packing rings 9 and 10 to protect the anti-friction rollers against gritty substances.

On the sleeve 7, and spaced apart therearound, there are the stabilizing ribs 11, three of said ribs being shown although the number may vary. These ribs allow space for the return of the drilling fluid.

These ribs extend longitudinally of the sleeve and are preferably seated in grooves therein and are welded thereto; although they may be secured in place in any preferred manner.

The ribs 11 are preferably quadrilateral in cross-section with their outer sides curved. Of course, the shape of the ribs may also vary. They radiate out from the sleeve so as to hold the sleeve with its axis approximately in coinciding relation with the axis of the bore.

The ribs 11 may be in the form of cutters hardened to present reaming cutters; however, these ribs may simply provide for engagement with the bore hole; and as later described may be of a friable material, such as cast iron or an aluminum alloy, or a plastic which is readily drillable.

The overall transverse diameter of the sleeve, including the ribs, is only slightly less than the transverse diameter of the bore hole so that the stem 2 and the drill will be maintained centered, or approximately centered, relative to the bore hole and this will prevent the drill from wobbling or wandering off of its true course.

The upper end of the coupling 3 is provided with J-slots spaced apart therearound. These slots are indicated by the numeral 12 and the lower end of the sleeve 7 is provided with the J-slots 13 which are reversely directed with respect to the slots 12. These slots 12 and 13 being spaced apart from projections 14 and 15 which project upwardly and downwardly, respectively, from the special coupling 3 and the sleeve 7.

Around the stabilizer stem 2 and seated within the projections 14 there is a strong coil spring 16 which forms a yieldable seat so as to prevent the projections 14, 15 from interengaging during normal drilling operations or when the drill stem is elevated relative to the sleeve 7.

In carrying on drilling operations the stabilizing ribs 11 will usually be in frictional contact with the walls of the well bore and the upper end of the stabilizing

sleeve 7 will be in contact with the anti-friction bearing assembly 6.

However, when it is desired to lower the drill stem and drill into, or withdraw them from, the bore hole it may happen that the stabilizing sleeve will become stuck in a restriction in the bore or in a sidewall key-seat. In such event the drill stem may be pulled upwardly with sufficient force to collapse the spring 16 so that the projections 14 will be brought into intermeshing relation with the projections 15 and upon rotation of the drill stem to the right said projections will interlock, by reason of the J-slots, thus forming a clutch so that the sleeve 7 will be caused to rotate with the drill stem and it will remain so interlocked while the drill stem is rotated and moved on down, or upwardly, so that the ribs will act as sidewall cutters to free the stuck stabilizer and the complete apparatus may be lowered on into, or withdrawn from, the well.

Described more extensively, it will be seen that the relative sliding movement of the bearing 7 and the drill stem section 2, which movement may be one or more feet in extent, provides for a jar. Thus assuming that the bearing 7 is stuck in the hole in the position shown in Figure 6, if the drill stem be now raised, the coupling 3 will strike the bearing so as to jar the same loose. If the drill stem is now rotated, causing the coupling parts 12 and 13 to engage, there will be a further jar and this jar will be quite pronounced, because as the coupling 3 and the bearing have engaged there will be a tension placed on the drill stem so that when the couplings mesh they will snap together. Since the depth of the coupling recesses can be made two or more inches, it will be seen that with the tension applied to the drill stem, the jar even here will be quite pronounced. Of course, the rather strong spring 14 will cushion the initial jar as the coupling 3 approaches the bearing 7; however, by that time the applied force is sufficient to overcome the spring so that there will be a pronounced jar. However, the tension of the drill pipe as the couplings mesh will be so pronounced as to far over-balance the tension of the spring. As these couplings now engage, the bearing 7, with its ribs 11, will rotate with the drill pipe, so that if the bearing is not fully disengaged from the formation it will become so disengaged.

As hereinabove indicated two or more of the stabilizers may be required in order to maintain a straight bore hole. With one stabilizer it may happen that the upper end of the drill collar may wobble, and in such case, while the stabilizer may not wobble, the oscillating movement would be transmitted to the drill bit and cause it to move radially. In such case it would be necessary to locate an additional stabilizer above the drill collar assembly. This second stabilizer will stop the radial movement of the upper part of the drill collar and the lower stabilizer will stabilize the drill bit and true rotation of the drill bit would be had at all times. However, in case several drill collars were used it is possible for the complete assembly to wobble midway between the two stabilizers, which movement would be transmitted to the drill bit and in such case a third stabilizer would be required in order to eliminate this oscillating movement.

In the present illustration, as shown in Figures 7, 8 and 9, three of said stabilizers are employed, one spaced above the drill, as shown in the other figures, such as in Figure 6, and the other stabilizers are spaced above any selected distance apart, said other stabilizers being indicated by the numerals 7a and 7b. They are of similar construction to the type of stabilizer 7 and are incorporated into similar organizations.

In accordance with the embodiment, Figure 10, the bearing of sleeve 7 will be simply rotatably mounted on the stem section by the roller bearing therein as in Figure 1. There is, however, another ball thrust bearing 60, placed beneath the bearing so as to confine the same between these two thrust bearings, and this ball bearing 60 is retained by a collar 61. The slots for the cutters 11 which may be slidably dovetailed into the bearing are then continued to the bottom of the bearing and retained by shear pins 62. It will be understood that in this embodiment the ball bearing 60 and the collar 61 are diametrically reduced so as to be inside the bottoms of the slots for the ribs or cutters 11. If in this case the bearing should become stuck, then by raising on the drill stem the pin 62 will shear so that

the body of the bearing may be raised. This will, of course, leave the ribs or cutters 11 in the hole above the bit, but by raising of the bit, these will be displaced and by making the ribs of a friable material, such as cast iron, or of an aluminum silicon alloy, or of a plastic such as Bakelite, these ribs can be readily drilled out.

The drawings and description disclose what is now considered to be preferred forms of the invention by way of illustration only and not by way of limitation, while the broad principle of the invention will be defined by the appended claims.

What I claim is:

1. In a drill stabilizer the combination comprising: a drill stem to the lower end of which a drill is attached; a stabilizer sleeve mounted on said stem above the drill for rotative and axial movement relative to said stem; external longitudinal cutters on said sleeve for holding said stem approximately centered relative to a bore being drilled; and J-slot clutch means on said stem and sleeve, respectively, engagement of said clutch means causing said sleeve to rotate together and move axially with said stem, whereby the walls of the bore will be cut away upon rotation of said stem.

2. A stabilizer for drills comprising: a tubular stem to the lower end of which a drill is adapted to be attached; a sleeve mounted on said stem for rotative and axial movement relative thereto; external spacers mounted on said sleeve for drill-stem-centering engagement with the walls of a bore being drilled; and J-slot clutch means on said sleeve and said stem adapted, when engaged, to connect said sleeve and stem together for rotation and axial movement as a unit.

3. A stabilizer for drills comprising: a tubular stem to the lower end of which a drill is adapted to be attached; 35

a stabilizer sleeve mounted on said stem for rotative and axial movement relative thereto, said sleeve having a plurality of longitudinal grooves; abutment means on said stem for limiting axial movement of said sleeve thereon; 5 external spacers on said sleeve for drilling stem-centering engagement with the walls of a bore being drilled, said spacers comprising longitudinal ribs fitting in said sleeve grooves; and yieldable means including shearable pin means fastening said ribs to said sleeve.

4. A stabilizer for drills comprising: a tubular stem to the lower end of which a drill is adapted to be attached; a sleeve mounted on said stem for rotative and axial movement relative thereto; means on said stems for limiting said relative axial movement; external spacers 10 mounted on said sleeve for drill-stem-centering engagement with the walls of a bore being drilled; and axially-engageable clutch means mounted on said stem and said sleeve for connecting said sleeve to said stem for rotation in both directions therewith and for axial movement in 15 both directions therewith.
